UNITED STATES PATENT OFFICE.

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK.

CAR-DOOR OPERATION.

Application filed May 1, 1925. Serial No. 27,268.

For a detailed description of the present form of my invention, reference may be had to the following specification and to the accompanying drawings forming a part thereof, wherein

Fig. 1 is a front view of my device partly in section;

Figs. 2 and 3 show details;

Fig. 4 is a plan and

Fig. 5 a side view.

My invention relates to apparatus for operating car doors by an electric motor through the intervention of a radial door arm. This combination permits the motor to immediately attain its normal constant speed by reason of its high leverage advantage over the door at starting and to maintain such constant speed through the entire run of the door while imparting to the door a gradual increasing speed from zero to maximum followed by a decreasing speed from maximum to zero. This eliminates the need for resistance regulation of the motor, also the need of checking agencies for the door, since the radial arm becomes—so to speak—a mechanical regulator for the motor, compensating mechanically, instead of electrically, for the extra inertia-load of the door at stopping and starting. I provide herein certain features of improvement in door apparatus of this type, including a simple form of clutch for disconnecting the motor from the door to allow the door to be worked manually.

Referring to the drawing, A represents the door with a channel B on its rear edge wherein travels vertically a roller c on the outer end of a radial arm C on the arm shaft D. The shaft D is operated by the shaft D² through a clutch. Y is the motor, driving shaft D² through the worm gear N and O O are limit switches operated by a bar O² on shaft D² at each end of its run. The arm C occupies the full-line position when the door is open and the dotted line position when it is closed, the rear edge of the door occupying when open the position a and, when closed, the position b. The arm C, when the door is open, is inclined upwardly from the shaft D and inclined downwardly therefrom when the door is closed, as appears in Fig. 1. By this means the door when closed is securely locked by the arm which is of particular importance if the

motor is unclutched from shaft D when the door might otherwise be jarred open. When the door is open the arm must be at or near the horizontal. Otherwise it would be difficult to stop it against the base of the motor and its extension spring R might collapse sufficiently to allow it to pass the horizontal where it would come up again with a jerk and cause a shock to the mechanism. The angle of the door arm is positively determined, in each of the two positions, by stops d and g on the base E of the motor. The shorter stop g is for the door-closed position and the longer stop d for the door-open position. Thus the run of the door is fixed independently of any yielding of the door jamb or of any rubber filling on the door-edge abutting against the jamb. Moreover, a bar F is hinged at one end to the base E of the motor and its free end has a cord or wire G secured to it which passes over a pulley T on the door-frame near the top of the door and terminates in a handle by which the bar may be manually lifted. On the upper edge of bar F is a short projection k and a longer projection f, these projections having offsets at their upper ends which take under the door arm C, the offset on shorter projection k when the arm is in its door-closed, and that on projection f when the arm is in its door-open position. In either position a pull on cord G will lift the arm from its locking position and so free the door for hand operation, if the motor is disconnected.

The arm-shaft D is in line with the motor-shaft D² and is clutched thereto by a toothed clutch-disc J thereon which engages with a companion clutch-disk K on motor-shaft D². The discs are pressed into engagement by a spring W on the door-shaft D, the disc J being free to slide longitudinally thereon. The discs are separated by means of yoke-arms p and q which bear on the face of disc J. The yoke and yoke-arms pivoted on the stationary framework at h, h, are operated by a treadle P to separate the discs against the pressure of spring W and when so operated a stud S on the yoke rides under a latch H and the discs are thereby locked apart. The door can then be operated by hand independently of the motor, which may at that time be disabled or not supplied with current. On the hub of clutch-disk K is a cam projection M, which, when the motor is

restarted will hit the tail of latch H and so release the yoke and permit spring W to throw the clutch discs into engagement. Thus when it is desired to operate the door by hand it is only necessary to step on treadle P. That will unclutch the door and motor and leave the clutch latched in its open condition. It will not be necessary to pay any further attention to the clutch, for when the motor is started again it will automatically re-engage itself with the door.

The apparatus above described constitutes a simplified development of that shown in my pending application, No. 6,788, series of 15 1925, filed February 4th, 1925, and is particularly useful in an arrangement wherein the shaft D² is driven by the motor through a screw-gearing, as shown herein, and in my application aforesaid. Any other type of 20 non-reacting gear may be used. In such an organization the manual operation, when the motor is disabled, is facilitated by the clutch that disconnects the motor from the door, leaving the latter free to be moved by hand.

25 What I claim as new and desire to secure by Letters Patent is:

1. A door operating mechanism comprising an electric motor, a door arm operated thereby and a manual clutch interposed between the door arm and said motor, said door arm being set to assume an angle with its free end below the horizontal when the door is closed so as to hold the door locked while the motor is unclutched and to assume 35 an angle above the horizontal when the door is open.

2. A door-operating mechanism comprising an electric motor, a clutch, a door-arm, and a lifter for the door-arm acting on the 40 arm in either the closed or open position of the door.

3. A door-operating mechanism comprising an electric motor, a clutch, a door-arm and a lifter for the door-arm having engaging means at different levels to engage the door-arm in either the open or closed 45 position of the door.

4. A door-operating mechanism comprising

ing an electric motor, a clutch, a door-arm and stationary stops for the door-arm at 50 different levels.

5. A door-operating mechanism comprising an electric motor, a radial door-arm, a manual clutch between the motor and the door, a clutch operating lever and a latch for 55 locking the clutch operating lever in its disengaged condition, said latch being supported independently of the lever.

6. A door-operating mechanism comprising an electric motor, a radial door-arm, a 60 manual clutch between the motor and the door, a clutch operating lever, a latch for locking the clutch in its disengaged condition, and motor-operated means for releasing the clutch.

7. A door-operating mechanism comprising an electric motor, a radial door-arm, a spring clutch between the motor and the door, a pedal controlling the disengagement of the clutch, a latch for locking the clutch 70 in its disengaged condition, and motor-operated means for releasing the clutch.

8. A door-operating mechanism comprising an electric motor, a radial door-arm, a clutch having a movable member on the door-arm shaft and the other member on a shaft in line therewith, a spring for the movable member, a pedal mounted on a stationary base for operating the said movable member, a latch for locking the movable member in its disengaging position and motor-operated means for releasing the clutch.

9. A door-operating mechanism comprising an electric motor, a non-reversing gear between the motor and the door, a radial door-arm, stationary stops for each extreme position of the door-arm, a manual lifter for each of said door-arm positions, a manual clutch between door-arm and the motor, a spring-actuated lock for the clutch in its disconnected position, and motor-actuated means for releasing said lock.

Signed at Albany, county of Albany, and State of New York, this 27 day of April, 1925.

LEE P. HYNES.
